TRELLIS

Walter H. Jacobsen, Ivyland, Pa., assignor to General Plastics Corporation of America, Philadelphia, Pa., a corporation of Pennsylvania

Filed Feb. 15, 1962, Ser. No. 68,834

Term of patent 14 years

(Cl. D54—2)

FIG. 2

FIG. 1 is a front elevational view of a trellis embodying my new design.

FIG. 2 is a top plan view of the same.

FIG. 3 is an end elevational view of the same.

The rear of the trellis, not shown, is substantially flat, plain, and unornamented.

I claim:

The ornamental design for a trellis, as shown and described.
